[57] CLAIM

The ornamental design for a clipboard light, as shown and described.

DESCRIPTION

FIG. 1 is a perspective view of a clipboard light showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is an underneath plan view thereof.

The clipboard is shown in broken lines for illustrative purposes only and forms no part of the claimed design.
